COMBINED COIN-CONTROLLED COFFEE PERCOLATOR AND DISPENSING MACHINE

Ford SeBastian, Merion, Pa., assignor to Coffee Chef Corporation, Merion Station, Pa., a corporation of Pennsylvania

Filed Oct. 21, 1963, Ser. No. 77,077

Term of patent 14 years

(Cl. D2—3)

FIG. 1 is a perspective view of a combined coin-controlled coffee percolator and dispensing machine viewed from one side thereof, showing my new design; and

FIG. 2 is a perspective view thereof taken from the opposite side, the end of the conventional electric cord being broken away for convenience of illustration.

The characteristic features of the disclosed design reside in the coin-control portion in association with the presence of the vents and the liquid-level viewer of the container.

I claim:

The ornamental design for a combined coin-controlled coffee percolator and dispensing machine, as shown and described.
